UNITED STATES PATENT OFFICE.

WILLIAM PRELLWITZ, OF EASTON, PENNSYLVANIA, ASSIGNOR TO THE INGERSOLL-SERGEANT DRILL COMPANY, OF NEW YORK, N. Y., A CORPORATION OF WEST VIRGINIA.

COMPRESSOR.

SPECIFICATION forming part of Letters Patent No. 792,790, dated June 20, 1905.

Application filed June 2, 1904. Serial No. 210,827.

To all whom it may concern:

Be it known that I, WILLIAM PRELLWITZ, a citizen of the United States, and a resident of Easton, in the county of Northampton and State of Pennsylvania, have invented a new and useful Improvement in Compressors, of which the following is a specification.

This invention consists in certain improvements in compressors for air and other aeri-form and gaseous bodies, and relates particularly to certain improvements in a compound single-acting compressor, whereby a compressor of this type is given much greater efficiency than has heretofore been possible.

15 A practical embodiment of this invention is represented in the accompanying drawing, which shows the compressor and its intercooler in longitudinal central section.

The low-pressure cylinder is denoted by 1, 20 its piston by 2, and its outer cylinder-head by 3. The high-pressure cylinder is denoted by 4, its piston by 5, and its outer cylinder-head by 6. The low and high pressure pistons 2 and 5 are connected to move simultaneously in the same direction by a piston-rod 7, and the low-pressure piston 2 is provided with an operating piston-rod 8, which passes through suitable packed bearings in the low-pressure outer cylinder-head 3.

25 Communication between the chamber 9 at the back of the piston 2 and the compression-chamber 10 at the front of the piston is controlled by an annular valve 11, which is arranged to control an annular port 12 in the 30 said piston.

Communication is opened and closed between the chamber 13 at the back of the piston 5 and the high-pressure compression-chamber 14 at the front of the piston by an 35 annular valve 15, which is arranged to open and close an annular port 16 in said piston.

An intermediate head 17 is located between the low and high pressure cylinders, which head forms the common inner cylinder-head 40 of the low and high pressure cylinders. The piston-rod 7 which connects the two pistons

is fitted to reciprocate in suitable packed bearings in the said intermediate head.

The low-pressure cylinder is supported upon a suitable base 18, and the high-pressure cylinder is supported by an upright 19, mounted on a floor or other suitable support 20. This upright 19 is hollow and forms the fluid-inlet 21. This fluid-inlet 21 communicates with a duct 22, located along the wall of the high-pressure cylinder, which duct opens into the supply-chamber 9 in the low-pressure cylinder.

55 The intercooler is denoted by 23. An outlet-port 24 for the low-pressure compression-chamber 10 is controlled by a puppet-valve 25, and a duct 26 leads therefrom to the inlet end 27 of the intercooler. A duct 28 leads from the outlet end 29 of the intercooler to the chamber 13 in the high-pressure cylinder back of the piston. The discharge-port of 60 the high-pressure chamber 14 in front of the piston 5 is denoted by 30, and it is controlled by a puppet-valve 31.

65 To gain access to the packed bearing for the piston-rod 7 in the intermediate head 17, I provide a manhole-cover 32 upon each side of the said packed bearing, one only of said manhole-covers being shown herein.

In operation as the low-pressure piston 2 is moved inwardly the valve 11 therein is opened, 75 permitting the fluid to pass into the chamber 10. As the piston is moved forward the fluid is compressed and forced past the puppet-valve 25 through the intercooler and into the chamber 13 back of the high-pressure piston 80 85 and from thence past the open valve 15 therein into the chamber 14. The next inward movement of the low-pressure piston 2 and corresponding outward movement of the high-pressure piston 5 will discharge the fluid from the chamber 14 by the puppet-valve 31 and at the same time draw in a new supply of fluid into the chamber 10 in front of the low-pressure piston.

90 It has heretofore been common to admit atmospheric pressure back of the low and high pressure pistons, the fluid from the intercooler

being led to the front end of the high-pressure cylinder and caused to enter the latter through a puppet inlet-valve. By using the intermediate head 17 I am enabled to keep 5 the intercooler-pressure back of the high-pressure piston, thus allowing the proportion of the two cylinders to be the same as if they were made double-acting and keep the maximum and mean strains the same at each end 10 of the stroke. Also any leakage of fluid past the high-pressure piston during compression will pass to the chamber having fluid raised above atmospheric pressure rather than to the atmosphere. Furthermore, in the common 15 form as the piston in the low-pressure cylinder was compressing the fluid, there was cooler-pressure on the inlet side of the high-pressure piston, this pressure helping the low-pressure cylinder to do its work. On the return 20 stroke, the high-pressure piston compressed the fluid, but had no cooler-pressure back of it to help it. To equal the mean effective pressure, it was necessary to compress to a higher pressure in the low-pressure cylinder than would be necessary with a compound 25 double-acting machine. By the use of the intermediate head, as herein described, the conditions are the same whether the machine is compound, double-acting, or single-acting.

What I claim as my invention is—

1. In a compressor, separated low and high pressure cylinders, valved pistons therefor, 35 inlets at the approximate ends of the cylinders and outlets at their other ends, and means for

leading the compressed fluid from the outlet of the low-pressure cylinder to the inlet of the high-pressure cylinder.

2. In a compressor, separated low and high pressure cylinders, valved pistons therefor, 40 inlets at the approximate ends of the cylinders and outlets at the other ends of the cylinders, an intercooler, and means for leading the compressed fluid from the outlet of the low-pressure cylinder through the intercooler 45 to the inlet of the high-pressure cylinder.

3. In a compressor, low and high pressure cylinders, valved pistons therefor, a common head separating the two cylinders, inlets at the adjacent ends of the cylinders, outlets at 50 the other ends of the cylinders, and means for leading the compressed fluid from the outlet of the low-pressure cylinder to the inlet of the high-pressure cylinder.

4. In a compressor, separated low and high pressure cylinders, valved pistons therefor, 55 open inlets at the approximate ends of the cylinders, valved outlets at the other ends of the cylinders, and means for leading the compressed fluid from the valved outlet of the 60 low-pressure cylinder to the open inlet of the high-pressure cylinder.

In testimony that I claim the foregoing as my invention I have signed my name, in presence of two witnesses, this 31st day of May, 65 1904.

WILLIAM PRELLWITZ.
